WATER CIRCULATION THERMOSTAT

Max Goldschmidt, London, England

Application June 22, 1937, Serial No. 149,645
In Germany August 5, 1936

2 Claims. (Cl. 236—34)

The invention relates to a device, especially for the control of the circulation of the cooling water in the internal combustion engines of automobiles.

Devices are already known which consist substantially of a thermostatic element which can expand or contract under the influence of its content, a liquid with a low boiling point, and thus actuate a control member, a disc valve or a throttle valve, to open or close the pathway of the cooling means in one or two directions. The aforesaid control members have the disadvantage that sometimes they cannot resist in the way that is necessary the pressure of the cooling means produced by the pump, resulting in unreliable work or damage.

The object of the present invention is to overcome these disadvantages by an arched guiding of the control member from one seat position to the other seat position, which is in the same plane.

The drawing illustrates one form of the invention wherein:

Figure 1 shows the structure according to a longitudinal section on line 1—1 of Fig. 3;

Fig. 2 shows it according to a longitudinal section on the line 2—2 of Fig. 3, and

Fig. 3 is a plan view of the structure with upper parts removed.

The control member is built into a housing, the upper part 1 of which carries the connections 2 and 3 for a line to the radiator and for a by-pass line to the cooling water pump. The lower part 5, connected liquid tight with the upper part 1, by means of the cap screw 4, terminates in the connection 6 for the line to the cooling water chamber of the engine. The upper part 1 is constructed in such a way that on its lower surface, inside of the housing, it has a number of openings 7, 8, and 9, of which the two latter belong to the line to the radiator, and the first to the by-pass to the pump. The lower surface of the upper part 1 is covered with a plate 10 of similar form, and provides a seat for the control member 11, also made in the form of a plate. In the control member 11 are two passages 20 and 21 which in the two end positions are brought into and out of coincidence with the openings 8 and 9, respectively, and when out of coinciding relation, opening 20 overlies opening 7. In order that no power-consuming sliding friction may take place between the control member 11 and plate 10, as in the case of an ordinary flat slide valve, the member 11 is

guided by levers or links 12 (in the drawing there are four), which are articulated or pivoted to bearing supports 13 on the plate 10. The member 11, therefore, travels through an arched pathway and is in contact with the plate 10 only in its two end positions.

The actuating device for the member 11 consists in a push rod 14, which is articulated to one end of a lever 15, the other end of which is mounted on an arch 16 that is rigidly connected with the plate 10. Also, on the plate 10, by means of the connecting piece 17, is fastened with some lateral flexibility a thermostatic element 18, serving to actuate the lever 15 and member 11. The driving force, expressed in the expansion or contraction of the element 18, is transmitted through the push rod 19 to the lever 15, which multiplies the extent of movement.

In the use of the invention the connections 6 may be made by means of a rubber hose with 20 the water jacket of the engine, and the connections 2 and 3 in a similar manner with the line to the radiator and the by-pass to the pump. When the engine is cold, the device is in the position shown in the drawing, that is, the 25 thermostatic element 18 remains in the contracted state and the member 11, correspondingly takes a position with relation to the plate 10 in which the passage 7 is open, so that when the engine begins to operate the cooling means 30 flows from there through the by-pass 3 and, without flowing through the radiator, flows back through the cooling water pump directly to the engine, for the purpose of rapidly heating the cooling means to the temperature favorable to 35 the continuous running of the engine. When that temperature has been attained, the thermostatic element 18, on account of the evaporation of the liquid enclosed in it, begins to expand, whereupon the push rod 19, the lever 15, and 40 with it the member 11, move to the right. This closes the passage way 7 to the by-pass line and opens the passages 8 and 9 to the radiator, so that the cooling means, partially at first and later completely, takes its way to the radiator, 45 where it is subjected to a rapid cooling. With a corresponding fall in the temperature of the cooling means and by means of the contraction of the thermostatic element 18, the process described is gone through in the reverse order.

The levers 12, by which the member 11 is suspended, give the latter an arched movement, and consequently no sliding friction is produced, as in the case of a flat slide valve, which in view of the comparatively small amount of power that 50

can be developed by the thermostatic element 18 could make the action of the member 11 unreliable. By the precipitation of the dissolved solid components in the cooling means, which 5 partially have the effect of forming scale, there would even be difficulty in the movement of a slide valve moved in a straight line. From the theoretically mechanical point of view, the end 10 positions of the member 11 are stable and the mean position unstable, as it cannot be moved from the end positions without overcoming a certain although not undesirably large counter force caused by the pressure of the cooling means.

15 What is claimed is:

1. A thermostatically controlled valve for controlling the flow of cooling means in an internal combustion engine, comprising a flat plate member having separated openings, a flat plate valve 20 adapted to be moved from one position to another over the member and being adapted in one position to open one opening in the member and to close the other opening and in the other position to open said other opening and close

said one opening, and means including a thermostat for moving the valve in an arcuate path over the member so as to separate the member and valve during such movement from one position to the other and to bring them substantially 5 into flat contact when each of such positions is reached.

2. A thermostatically controlled valve for controlling the flow of cooling means in an internal combustion engine, comprising a flat plate member having separated openings, a flat plate valve adapted to be moved from one position to another over the member and being adapted in one position to open one opening in the member and to close the other opening and in the other 15 position to open said other opening and close said one opening, means for moving the valve over the member from one position to the other while maintaining the valve parallel to the plate and for bringing the valve and plate into substantially flat contact when each position is reached, and a thermostat for controlling said means so as to effect said valve movement.

MAX GOLDSCHMIDT.
